UNITED STATES PATENT OFFICE

WILLIBALD TRINKS, OF PITTSBURGH, PENNSYLVANIA, ASSIGNOR TO MESTA MACHINE COMPANY, OF PITTSBURGH, PENNSYLVANIA, A CORPORATION OF PENNSYLVANIA

METHOD OF OPERATING PICKLING MACHINES

Application filed June 26, 1929. Serial No. 373,742.

This invention relates to an improved method of operating pickling machines such as shown for example in the patent to Mesta No. 1,107,821 issued March 26, 1929. 5 In such machines the load is partly balanced by compressed air acting against the piston rod and is lifted by steam acting against a piston. The higher the counter-balancing air pressure, the lower can be the 10 steam pressure or the smaller can be the diameter of the piston. In either case, the steam consumption is materially reduced. However, any attempt to reduce the steam consumption is likely to result in a decrease 15 in speed of operation by reason of the fact that while the mass to be moved remains approximately the same, the effective downward force for accelerating the mass becomes very small if the counterbalancing air pressure is increased in too great an amount. The number of actuations of the machine in a given period of time is thus reduced and the time required for a complete cycle of operations is lengthened, 20 thus offsetting the saving in steam. Obviously there is an optimum air pressure in the balancing chamber of such value that it saves as much steam as possible without noticeably slowing down the operation of the machine. For a given machine such 25 optimum air pressure will vary with the particular loads being handled.

An ordinary operator cannot be expected unassisted to find the best air pressure for different loads and my invention provides a method whereby such optimum pressure may be readily determined by him. I provide for determining the optimum air pressure for a given load, either by calculation 40 or by test and for adjusting the fluid balancing pressure for the load being handled to substantially this predetermined optimum pressure. The load may be readily measured by balancing with whatever air pressure 45 then exists in the counterbalancing chamber plus such steam pressure as may be required. The balancing is done by slowly closing the steam supply valve when the moving parts of the machine with their load are at the top position and by reading

the steam and air pressures indicated as soon as the moving parts of the machine begin to sink. The optimum air pressure is preferably determined from these readings by means of a specially prepared chart 55 which has been made up by calculation or by previous tests.

In the accompanying drawing illustrating the present preferred embodiment of the invention, 60

Figure 1 is a transverse section through a pickling machine equipped for carrying out my invention and Figure 2 shows one form of chart which may be employed.

The pickling machine shown in Figure 1 65 is a well-known type comprising a standard 2 supporting a steam cylinder 3 and having incorporated in it an air cylinder 4. The moving parts of the machine are carried on a piston rod 5 having a piston 6 thereon. 70 The piston rod 5 extends through the steam cylinder 3 into the air cylinder 4. It projects above the steam cylinder 3 and carries arms 7 from which the carriers 8 for material to be pickled are hung. The pickling 75 and washing vats are indicated at 9.

Counterbalancing air is supplied through a pipe 10 having a valve therein and excess air may be taken off through a valved pipe 11. A gauge 12 is provided for reading 80 the air pressure in the cylinder 4. Steam for raising the moving parts of the machine is supplied to the cylinder 3 below the piston 6 through a valved pipe 13. The pipes for supplying and releasing steam are 85 well known and need not be described in detail. A gauge 14 is supplied for reading the steam pressure in the cylinder 3.

Assume that it is desired to pickle articles or bundles of articles of a certain weight. 90 The machine is loaded and without disturbing the air pressure then existing in the cylinder 4, steam is admitted below the piston 6 so as to raise the load. The steam pressure is gradually released until the moving parts of the machine begin to lower 95 and the steam and air pressure are then read from the gauges 14 and 12. In Figure 2 there is shown a chart for determining from these gauge readings the optimum 100

balancing pressure. In this chart the observed steam pressure is read along the bottom of the chart. The chart lines indicate different observed air pressures and the 5 optimum balancing pressure is read along the vertical scale of the chart.

Assume, for example, that the loads are such that the steam gauge shows a reading of 50 pounds and the air gauge reads 60 10 pounds;—starting at 50 on the horizontal scale of the chart and moving upwardly to the line corresponding to 60 pounds observed air pressure we read across to the left and find that the optimum balancing 15 pressure to be maintained in the cylinder 4 for minimum steam consumption is 85 pounds. Machines of this character are or may be equipped with control mechanism to introduce and maintain the proper pres- 20 sure in the balancing chamber.

The chart of Figure 2 may be readily constructed. A machine carrying an average load is operated with successively higher pressure in the balance cylinder. The 25 speed of the machine and the time required for good pickling are noted. That balancing air pressure at which a quick falling off of the pickling speed occurs is observed and the best balancing pressure is decided 30 upon at a safe distance below that point. This process is repeated for a load considerably less than average and also for a load considerably more than average. The steam pressure which, together with the 35 optimum balancing pressure, supports the load during slow dropping from top position is noted, and the sum of the products (effective air plunger area $\times$ air pressure) and (effective piston area $\times$ steam pressure) 40 is computed. This sum is equal to the total weight lifted but for such total weight lifted the best balancing air pressure is known from the tests and the chart is designed to arrive at the above sum by taking 45 the readings above described.

It will be understood, of course, that instead of a chart using rectangular coordinates, alignment charts, slide rules, tabulations or other devices may be resorted to.

50 The experimental work of observing the best balancing pressure for a given load is determined but once by the builder of the pickling machine and thereafter the method herein described can be carried out by the 55 average operator without difficulty. I have illustrated and described a present preferred embodiment of the invention. It will be understood, however, that it is not thus limited, but may be otherwise em- 60 bodied or practiced within the scope of the following claims.

I claim:

A method of operating a pickling ma- 65 chine having an air balancing means and a steam lifting means which comprises evalu-

ating for various loads the highest air pressure at which rapid lowering of the respective loads can be effected, and the relation of the load carried at any time to the air and steam pressures required to balance it, 70 embodying these relations in a calculation-saving device, and adjusting the air pressure for the loads being handled in accordance with the pressures indicated by said device. 75

In testimony whereof I have hereunto set my hand.

WILLIBALD TRINKS.
